UNITED STATES PATENT OFFICE

HAROLD H. ROBINSON, OF OPA LOCKA, FLORIDA

DESIGN FOR A MOTOR VEHICLE

Application filed April 2, 1932. Serial No. 43,372. Term of patent 14 years.

To all whom it may concern:

Be it known that I, HAROLD H. ROBINSON, a citizen of the United States, residing at Opa Locka, in the county of Dade and State of Florida, have invented a new, original, and ornamental Design for Motor Vehicles, of which the following is a specification, reference being had to the accompanying drawing, forming part thereof.

In the drawing:

Fig. 1 is a side view of the motor vehicle;

Fig. 2 is a front view thereof; and

Fig. 3 is a rear view thereof.

The present design comprises as the principal and dominating feature thereof a relatively long and slender wheel supported body with rounded front and rear ends, the rounding of the front end being more blunt than that of the rear end, and the supporting wheels for said body being only partially exposed at the lower side thereof.

I claim:

An ornamental design for a motor vehicle, substantially as shown and described.

HAROLD H. ROBINSON.
